UNITED STATES PATENT OFFICE

REUBEN C. BAKER, OF COALINGA, CALIFORNIA, ASSIGNOR TO BAKER OIL TOOLS, INC.,
A CORPORATION OF CALIFORNIA

WELL-CASING-CENTERING DEVICE

Application filed January 31, 1928. Serial No. 250,830.

This invention relates to auxiliary devices or apparatus employed during the drilling and casing of oil and gas wells.

In drilling oil and gas wells, it is common practice to drill the hole to a point closely adjacent to the productive zone, and then case the well. After the casing has been properly positioned, it is cemented in by forcing cementitious material from the bottom of the casing upwardly around the casing to fill the space between the latter and the sides of the bore. Oft times the casing does not properly center in the hole but assumes an eccentric position therein and bears against one side thereof. This usually prevents properly cementing in of the casing, particularly, when the hole is filled with heavy drilling mud, as the cement has insufficient force to displace all of the mud and consequently cannot entirely envelop the casing. Therefore, the cement channels through the mud during its upward travel, leaving the casing encased partially in mud and partially in cement. This is unsatisfactory as there is nothing to prevent the mud from running down into the bore, permitting water from upper formations to flow into the bore unobstructed.

It is the principal object of the present invention to overcome this disadvantage in prior practice by providing simple apparatus capable of retaining the casing centered in the bore and assisting the cement during the cementing operation to entirely envelop the casing.

In carrying out the invention into practice, I provide a centering apparatus which is carried by the casing and engages the sides of the bore to hold the casing centered therein and spaced from the sides of the bore. The apparatus permits the filling of the space between the casing and the bore and aids in the cementing operation by assisting the cement in enveloping the casing by causing the cement to travel in a spiral path, so that it will entirely surround the casing.

One form which the invention may assume is exemplified in the following description and illustrated by way of example

in the accompanying drawings, in which:

Fig. 1 is a fragmentary view in section through a well bore disclosing a casing therein upon which my improved apparatus is assembled.

Fig. 2 is a transverse section through a well casing disclosing my improved device assembled thereon and illustrating it in plan.

Fig. 3 is a perspective view of the device.

Referring more particularly to the accompanying drawings, 10 indicates the bore of a deep well wherein a well casing 11 is disposed. Arranged on the casing is a plurality of centering devices indicated by the numeral 12, which devices form the subject matter of the present application.

Each centering device comprises a circular member 14 having radial ribs 15 projecting inwardly therefrom at equally spaced distances apart. The circular member 14 is formed in two halves, the ends of which are connected together as illustrated in Fig. 2.

The ribs 15 are arranged spirally with respect to the longitudinal axis of the device, so that when the centering device is arranged on a well casing the ribs will engage the periphery thereof, holding the circular member concentrically with respect to the casing and forming a plurality of spirally disposed passageways 16 between the circular member and the casing.

It is intended that the diameter of the circular member be substantially the same as that of the well bore so that the circular member will engage the sides of the bore and maintain the well casing substantially centered therein.

Extending through each rib 15 of the device is a screw 17 utilized to secure the centering device on the casing.

It will be noticed that the exterior surface of the circular member is rounded longitudinally thereof, so that it will pass downwardly into the bore easily.

In operation of the device, centering guides are constructed as illustrated in the drawings and a series of them are arranged at spaced distances apart on the casing as

the latter is lowered into the hole. The exterior surfaces of these devices will engage the well bore and maintain the casing substantially centered therein.

5 After the casing has been lowered to position in the hole, cement is ejected from a point at or adjacent its lower end and caused to travel upwardly between the casing and the sides of the bore. As the cement passes 10 through the passageways 16, it will be given a spiral movement to cause it to completely envelop the casing. This spiral movement of the cement will be caused by the spirally arranged passageways between the circular member and the casing and the spiral ribs.

15 It is obvious from the foregoing that I have provided simple means for overcoming the disadvantages of prior methods by holding the casing properly centered in the 20 hole and assisting the cement in completely enveloping the casing.

While I have shown the preferred form of my invention, it is to be understood that various changes may be made in its construction 25 by those skilled in the art without departing from the spirit of the invention as defined in the appended claims.

Having thus described my invention, what I claim and desire to secure by Letters 30 Patent is:

1. A device of the character described comprising a member adapted to be fixed on the exterior of a well casing and engage the sides of a well bore to maintain the casing spaced from the sides of the bore, said member having spirally formed passageways formed therethrough to assist cementitious material in enveloping the casing, said member being formed in separable 35 parts whereby it may be assembled and clamped on a well casing.

2. A device of the character described comprising a circular member of a diameter larger than the exterior diameter of the 40 casing, radial ribs carried by the member and projecting inwardly to engage the exterior surface of the casing to dispose said member concentrically of the casing, said member being formed in separable parts whereby it may be assembled and clamped on a well casing.

3. A device of the character described comprising a circular member of a diameter larger than the exterior diameter of the 45 casing, radial ribs carried by the member and projecting inwardly to engage the exterior surface of the casing to dispose said member concentrically of the casing, said ribs being arranged at an angle to the axis 50 of the casing to form spiral passageways between the casing and member to assist cementitious material passing along the well bore to completely envelop the casing, and means securing said member to the casing.
